(57) **CLAIM**

The ornamental design for a rolling toy, as shown and described.

DESCRIPTION

FIG. 1 is a front view of a rolling toy in accordance with a first embodiment of my design, the rear view being identical thereto;

FIG. 2 is a right side view of the rolling toy of FIG. 1, the left side view being a mirror image thereof;

FIG. 3 is a top view of the rolling toy of FIG. 1;

FIG. 4 is a bottom view of the rolling toy of FIG. 1;

FIG. 5 is an exploded front view of the rolling toy of FIG. 1, showing the three components of the rolling toy; and,

FIG. 6 is an exploded, side view of the rolling toy of FIG. 1, showing the three components of the rolling toy as illustrated in FIG. 5.
